CLAIM

The ornamental design for an atomization core for electronic cigarette, as shown and described.

DESCRIPTION

FIG. 1 is a front elevation view of a first embodiment of an atomization core for electronic cigarette;

FIG. 2 is a rear elevation view of the first embodiment thereof;

FIG. 3 is a left side elevation view of the first embodiment thereof;

FIG. 4 is a right side elevation view of the first embodiment thereof;

FIG. 5 is a top plan the view of the first embodiment thereof;

FIG. 6 is a bottom plan the view of the first embodiment thereof;

FIG. 7 is a perspective view of the first embodiment thereof;

FIG. 8 is a front elevation view of a second embodiment of thereof;

FIG. 9 is a rear elevation view of the second embodiment thereof;

FIG. 10 is a left side elevation view of the second embodiment thereof;

FIG. 11 is a right side elevation view of the second embodiment thereof;

FIG. 12 is a top plan the view of the second embodiment thereof;

FIG. 13 is a bottom plan the view of the second embodiment thereof;

FIG. 14 is a perspective view of the second embodiment thereof;

FIG. 15 is a front elevation view of a third embodiment of thereof;

FIG. 16 is a rear elevation view of the third embodiment thereof;

FIG. 17 is a left side elevation view of the third embodiment thereof;

FIG. 18 is a right side elevation view of the third embodiment thereof;

FIG. 19 is a top plan the view of the third embodiment thereof;

FIG. 20 is a bottom plan the view of the third embodiment thereof; and,

(Continued)

FIG. 21 is a perspective view of the third embodiment thereof.
